(57) **CLAIM**

The ornamental design for an electric lamp socket pin, as shown and described.

DESCRIPTION

FIG. 1 is a top perspective view of an electric lamp socket pin showing my new design;

FIG. 2 is a side elevation view thereof;

FIG. 3 is another side elevation view thereof;

FIG. 4 is a top plan view thereof; and,

FIG. 5 is a bottom plan view thereof.

The broken lines in the drawing views represent unclaimed portions of the electric lamp socket pin, which are shown for illustration purposes only and form no part of the claimed design.
